UNITED STATES PATENT OFFICE.

JOSEPH C. WISE, OF REDWOOD CITY, CALIFORNIA, ASSIGNOR OF ONE-FOURTH TO
EMMA MEYERS, OF OAKLAND, CALIFORNIA.

BOOKMARK.

Application filed May 31, 1922. Serial No. 564,845.

To all whom it may concern:

Be it known that I, JOSEPH C. WISE, a citizen of the United States, and a resident of Redwood City, county of San Mateo and State of California, have invented a new and useful Bookmark, of which the following is a specification.

My invention relates to an improved combination envelop and bookmark or rather a bookmark that may be made from discarded envelops so that the envelop may be made to serve two purposes and even a third when it is considered that the combination of the two stated uses offers a unique advertising feature.

The invention is illustrated in the accompanying drawing in which Figure 1 is a face view of the envelop showing the application of the invention; Figure 2 is a view of the back of the envelop and Figure 3 is a view of the back of the bookmark after it has been cut out; the dotted lines show the margin of the discarded part of the envelop.

Referring now to the drawing in detail A represents an envelop, having the customary sealing flap B on the back thereof.

According to my invention I mark off a horn shaped area (5) preferably in the left hand upper corner of the face and border the same as at (6) with dotted lines around the outside of the border as at (7). The dotted lines extend across the back as at (8) to leave a triangular area as at (9).

The inside of the horn-shaped area may be utilized for a return address and other advertising matter appropriate when the bookmark is used.

When the envelop is sent through the mails the flap B is pasted down and after it

has been opened by the addressee it may be 40 cut around the dotted lines (7) and (8) leaving the bookmark. The triangular area (9) together with the large end of the horn-shaped area or rather the corner of the cut-out will leave a pocket to receive the corner 45 edges of the book pages.

From the above it will be seen that I have produced a novel advertising device as well as an article which will supply a need.

I claim:

1. An envelope including a front having a diagonal line along which the same is adapted to be severed to produce one side of a book mark, said diagonal line also marking off one corner of the envelope for advertising matter; and a back integral with said front and having a diagonal line along which the same may be severed to form another side of a book mark. 55

2. The herein-described method of making 60 a book mark which consists in severing one corner portion of the front side of an envelope along curved lines to produce an approximately horn-shaped member, and in severing that portion of the back of the envelope immediately behind and integral with said horn-shaped portion whereby to define a pocket between the front and back of the envelope. 65

3. A book mark comprising front and rear 70 sides connected along the outer edges thereof and defining a triangular pocket adapted for the reception of one corner of a book page, said front side being adapted to bear advertising matter and having a horn-shaped ex- 75 tension.

JOSEPH C. WISE.
